GARMENT

Harry Goldstein, New York, N. Y.

Application August 30, 1935, Serial No. 38,506

2 Claims. (Cl. 2—224)

This invention relates generally to garments of the type which engage and encase portions of the body and the legs of the wearer. While I have herein illustrated my invention as embodied in the undergarment of a "panty" type for women, it will be understood that this is done only for purposes of exemplification.

As to its broader phases, my invention is capable of employment in garments of all types adapted for encasing the lower body portions and the legs or portions thereof. It is capable, for example, of employment in women's underwear, such as bloomers, panties, drawers and the like, including those supported from the shoulders, and generally referred to as "combinations", and is equally capable of employment in men's undergarments, and in outer garments as well.

The general objects of my invention are the provision of a garment of the type above referred to, which will be form-fitting, will snugly and smoothly engage the body parts and yet will not interfere with or render uncomfortable, changes in posture or position.

I attain this object generally as follows: I construct the garment so that it has a subthoracic portion relatively narrow at the waist-line, and increasing in width downwardly toward the seat portions until a maximum is reached after which it decreases in width, and these changes in width being such that the contour of the body is followed, and springing downwardly from said subthoracic portion are two downwardly tapering leg portions. These effects are calculated to make the garment form-fitting, and are attained by the juncture of oppositely curved edges of material, the curvatures being convexly opposed to each other, where an outward bulge is desired in the garment, and concavely opposed to each other where the reverse effect is desired. While I have shown the contours of these curved edges as mirror images of each other and their juncture as a mirror image relation, and while it is obvious that this is a very practical, and economical construction, it is to be understood that the contemplated effects may be approximated without a strictly mirror image relation, and that such constructions are also within the purview of my invention.

I so construct the seat portion that it will be form-fitting when the wearer is standing erect, and yet will provide that additional amount of seat fullness as to permit the wearer to bend without impairing the form-fitting character of

the garment, and without bringing about any discomfort or binding effect.

For the details of one embodiment of my invention, by which I attain the aforementioned objects and such other objects as will hereinafter appear or be pointed out, I will refer to the drawing, wherein:

Figure 1 is a front view of my garment;

Figure 2 is a section corresponding to the line 2—2 of Figure 1, looking in the direction of the arrows, but indicating the garment in place on a wearer;

Figure 3 is a view similar to Figure 2 showing the effect on the garment when the wearer bends her body forward and downward at the waist and hips; and

Figure 4 is a diagrammatic view showing the lay-out of all the parts needed for the assembly of the main parts of a complete garment in the relative positions they occupy.

Referring to the drawing, it will be observed, that I have shown a garment of the "panty" type, comprising a pair of symmetrically arranged front pieces A—1 and A—2, these being identical in contour. When the material employed has a right and a wrong side, these pieces are preferably made mirror images of each other, so that when they are joined in symmetrical fashion, the right side of the material will be on the same side in both pieces.

It will further be observed that the garment comprises two symmetrically arranged back portions B—1 and B—2, these also, being of identical contour, being cut as mirror images of each other when advisable. The same may be said for the inner leg portions C—1 and C—2.

Referring again to the front portions, of which it is only necessary to describe one, because of the aforementioned symmetry of contour, it will be observed that the front portion A—1 may be considered as comprising an abdominal portion that extends from the waist portion thereof downward toward the intermediate point 22, below which is a leg portion that runs from the point 22 downward. The upper edge of the piece A—1 is shown as bounded by a substantially straight line 21—25, and the front edge of the abdominal portion running downward from the point 21 to the point 22, and the front edge of the leg portion, running from the point 22, to the point 23, are both shown as substantially straight, but disposed at a slight angle to each other. The lower edge 23—24 is also shown as substantially straight. The side edge of A—1 runs from

55

the point 24 to the point 25, and it will be observed that it is shown as slightly convex.

The back portions, of which only one, B-1, will be described, may be considered as comprising a seat forming portion, which extends from the waist-line to an intermediate point 32, and a leg portion extending from the point 32 downward. This section is shown as having a substantially straight upper or waist edge 31-35, and a convexly curved side edge, uniting the point 35 at the waist with the lower extremity 34 of the leg portion. A substantially straight edge 34-33 forms the lower extremity of the leg portion, and the rear edge of the leg portion running from the point 32 to the point 33 is shown as contoured along a compound curve, being convex at its lower part and concave at its upper part. The upper concave part merges into the convexly curved seat portion 32-31.

20 In the assembled garment, the point 32 will approximate the apex of the crotch.

The inner leg portions, of which also only one, C-1, will be described, are shown as having four edges, of which two, 41-44 and 44-43 are substantially straight, and these may be described respectively as the front edge and the bottom edge of this portion. The front edge 41-44 is of the same length as the edge 22-23 of A-1, so that it will match it accurately and may be joined thereto. The upper edge connecting points 42 and 41 is concavely curved, while the rear edge, connecting the points 42 and 43 is compoundly curved, first convex, adjacent the point 42, and then concave, and it is a mirror image 35 of the edge 32-33 of portion B-1, so that it is adapted for being joined thereto.

The joining of these various parts has been indicated in the diagrammatic showing of Figure 3 by dot-and-dash lines, and it will be observed 40 that the abdominal portion of the garment is formed by uniting the edge 21-22 of A-1 with the edge 121-122 of A-2, and edge 31-32 of B-1 with edge 131-132 of B-2, and further uniting the front and the back sections so formed 45 along their lateral edges, that is, the section B-1 will have its edge 35-34 united to the edge 25-24 of A-1, and the section B-2 will have its edge 135-134 united to the edge 125-124 of A-2.

The inner leg portions C-1 and C-2 are applied, so that the edge 142-143 of C-2 is united 50 to edge 132-133 of B-2 and the edge 141-144 of C-2 to edge 122-123 of A-2, thereby forming a cylindrical leg portion. Similar operations effect union of C-1 to B-1, and the upper edges 55 41-42 and 141-142 of C-1 and C-2, thus forming the crotch portion.

It will be observed that at the points indicated by 22, 122, 41, 141, four of the sections meet, namely sections A-1, A-2, C-1 and C-2, and 60 at the point indicated by the numerals 32, 42, 132, 142, four sections also meet, namely, B-1, B-2, C-1 and C-2.

I have shown my garment made of six pieces, because I have found that in this way I can cut 65 the material efficiently and that furthermore, I can more definitely attain the form-fitting effect. It will be understood, however, that wherever two sections are joined edge to edge, along edges that are straight, it is generally possible to cut 70 both sections in one, and that therefore it is possible to attain the general objects of my invention by employing varied numbers of pieces both in excess of and less than the number shown in the drawing.

75 It is further to be observed that the uniting

of the curved edges, such as for example the edges 132-133 of B-2 and 142-143 of C-2, may be conveniently done by superposing the pieces so that the edges to be united coincide, and then applying the seaming stitches.

5

Attention will now again be called to the drawing, and particularly to Figures 2 and 3, which show the effectiveness of my invention in making a garment form-fitting. Figure 2 shows the garment fitted around a human figure in erect position and it will be observed that the garment increases in girth from the waist down, so as to provide for the corresponding increase in width of the body until the maximum girth is reached, this maximum being reached approximately at the point 32 of B-1. Thereafter the girth decreases, and the rate of decrease increases progressively downward, this change in girth being due to the convex contour of the joined edges of the various pieces at these points. The leg portions are tapered downwardly, but in the leg portions the rate of taper decreases progressively, being a maximum at their upper portions. This conformation is due to the concave contour of the rear edges of portions B-1 and B-2 and C-1 and C-2 which is so pronounced that it is not offset by the slight convexity of the front edges of B-1, B-2, and the rear edges of A-1 and A-2. The last mentioned convexity at the same time accomplishes a form-fitting outward flare at the thigh portions.

15

As is clearly observable from Figure 2 the resulting contours are such as to fit the body as closely as is consistent with freedom of motion, fulness being provided only where needed to permit such movement. As will be observed from Figure 3, which shows the body bent forwardly and downwardly from the hips, the fulness that appears in places in Figure 2 does not represent unnecessary excess material, but only added material that is necessary to permit such free bending movement.

25

In this connection attention is called to the fact that garments constructed according to my design are intended to, and have, a greater amount of material available to permit the bending such as in Figure 3 than garments of ordinary design. In such garments of ordinary design, for example, the back portion of the part B-1 might be cut along the dotted line 31-32' 50 of Figure 4, and the corresponding cut in section B-2 would be along dotted line 131-132' of Figure 4. It therefore appears that my garment has added thereto, over the material of the ordinary garment the portion to the left of the dotted line of B-1, and to the right of the dotted line of B-2, thereby providing fulness positioned and distributed to give the desired effect and to eliminate the bunching effect present in a conventional garment because of the improper distribution of the fulness around the points 32' 55 and 132'. 60

40

Attention is also called to the increase in the length of the seam line at the back, which is very apparent when the length of the rear curved edge of B-1 and B-2 in garments made according to my design are compared to the straight line cuts of the ordinary garments as indicated in dotted lines.

65

It will also be obvious that the same desirable effects can be produced in other garments, such as combination garments, and that such effects are not restricted merely to articles of under-wear, but may be found equally useful in garments for outer wear. It will further be observed 70

75

that due to their form-fitting characteristics, articles of clothing made according to my invention may be made of all fabrics, both knitted or woven.

5 It is almost superfluous to state that to the basic constructional features, as hereinabove outlined may, be added the touches looked for in a finished garment, such as hemming, where required, together with ornamental touches as desired. It will also be observed from Figure 1, that I have shown my garment provided with an elastic waist band 15.

By again referring to Figure 4 it will be observed that the vertical distance from the waist line to the bottom of the leg portions increases from the front of the garment to the back of the garment, being least at the middle of the front portion and greatest at the rear of the back portion. It will also be observed that since 20 one of the principal determining factors in the amount of stretch at the rear portions of the garment is the length of the seams at such rear portions, that the provisions made in my garment in this respect are unusually ample. Whereas, 25 in the ordinary garment such rear seam might differ in length very little from the vertical height of the garment at its rear portion, in my garment the length of this seam is represented by the length of the compoundly curved rear 30 edge 31—33, which greatly exceeds said vertical height, and this length of seam is adapted to follow the body curves in the forward bending of the body as shown in Figure 3 and to distribute the fullness where it is required.

35 While I have disclosed herein one embodiment of my invention, it is to be understood that the same may be embodied in many other forms as will be obvious to those skilled in the art without departing from the spirit thereof, and it is 40 to be understood that the disclosure herein is intended to be illustrative merely and not limiting in any sense, and that I do not limit myself other than as called for by the specific language of the appended claims.

45 Having thus described my invention and illustrated its use, what I claim as new and desire to secure by Letters Patent, is:—

1. A bifurcated nether garment comprising a front portion consisting of an abdominal portion and two leg portions projecting downwardly therefrom, said abdominal portion tapering upwardly and, said garment comprising further a 5 back portion consisting of symmetrically contoured lateral sections, each comprising a seat portion having a convexly curved rear edge, and a leg portion having a compoundly curved rear edge, convex at its upper portions and concave 10 at its lower portions, and said sections being joined along said convexly curved rear edge of the seat portion, and said garment having further inner leg portions, each having its rear edge compoundly curved and contoured so that it is 15 a mirror image of the aforesaid compoundly curved rear edge and united to said compoundly curved rear edge, and said portions being dimensioned so as to provide fullness at the seat and adjacent parts of the garment, said garment at 20 other points thereof being substantially closely form-fitting.

2. A bifurcated nether garment comprising a front portion consisting of an abdominal portion and two leg portions projecting downwardly 25 therefrom, said abdominal portion tapering upwardly, said garment comprising further a back portion consisting of symmetrically contoured lateral sections, each comprising a seat portion having a convexly curved rear edge, and 30 a leg portion having a compoundly curved rear edge, convex at its upper portions and concave at its lower portions, and said sections being joined along said convexly curved rear edge of the seat portion, said garment having further 35 a pair of symmetrically contoured inner leg portions, each having its rear edge compoundly curved and contoured so that it is a mirror image of the aforesaid compoundly curved rear edge and united to said compoundly curved rear edge 40 and having its upper edge concavely curved and united to the similar edge of the other inner leg portion, said portions being dimensioned so as to provide fullness at the seat and adjacent parts of the garment, said garment at other points 45 thereof being substantially closely form-fitting.

HARRY GOLDSTEIN.
